His Attorney

UNITED STATES PATENT OFFICE.

CHARLES W. DUNHAM, OF WILKINSBURG, PENNSYLVANIA, ASSIGNOR TO THE UNION SWITCH & SIGNAL COMPANY, OF SWISSVALE, PENNSYLVANIA, A CORPORATION OF PENNSYLVANIA.

ELECTRIC SIGNAL.

Application filed December 7, 1923. Serial No. 679,057.

My invention relates to electric signals, and particularly to signals of the type comprising a signal arm arranged to oscillate. Signals embodying my invention are particularly adapted for, though in no way limited to, use as highway crossing signals.

I will describe two forms of signals embodying my invention, and will then point out the novel features thereof in claims.

10 In the accompanying drawing, Fig. 1 is a view, partly diagrammatic, showing in front elevation, one form of signal embodying my invention. Fig. 2 is a view showing a modification of the signal illustrated in Fig. 1. 15 Figs. 3 and 4 are detail views showing parts of the signal shown in Fig. 2. Fig. 5 is a detail view showing, in side elevation, the magnet A shown in Fig. 1. Fig. 6 is a view showing another modification of the signal 20 illustrated in Fig. 1 and also embodying my invention.

Similar reference characters refer to similar parts in each of the several views.

Referring first to Fig. 1, the signal comprises a signal arm B pivotally supported on a shaft 4. This arm carries at its lower end a target 3 which may be provided with some suitable warning legend, as the word "Stop". Supported also on shaft 4 is a yoke C of magnetizable material comprising two downwardly projecting diverging legs 6 and 7. These legs are separately and independently pivotally mounted on the shaft 4. Legs 6 and 7 are provided with outstanding lugs 6^a and 7^a, respectively, arranged to engage arm B, and the parts are so disposed that they are biased by gravity into the position in which they are shown in the drawing. Under these conditions arm B 40 assumes a central position and the parts are in equilibrium.

An electromagnet A, having two spaced poles 2 and 2^a connected by a back strap 20 and each pole provided with a winding 1 as shown in Fig. 5, is so disposed that the poles 2 and 2^a extend upwardly between the legs 6 and 7 of yoke C. Each leg 6 and 7 preferably bridges the poles 2 and 2^a of magnet A.

50 Arm B operates a circuit controller J as follows:

The upper end of arm B extends beyond the pivot 4 to form a projection 5 which enters a recess 8^a in a plate 8. This plate 55 is supported by means of two pins 9 and 9^a

which project into slots 10 and 10^a respectively in the plate 8. The upper edge of plate 8 is provided with a conducting strip 11 arranged to co-operate with two fixed contact members 12 and 13 so that when 60 arm B is in its central position, contact 12—11—13 is closed. If arm B is swung to the right, projection 5 engages the edge of recess 8^a and moves plate 8 to the left thus breaking contact 11—13. If the arm B is swung 65 to the left the plate 8 is shifted in the other direction and contact 11—12 is broken. It should be noted that there is considerable clearance between projection 5 and the edges of recess 8^a and therefore there is considerable lost motion between arm B and plate 8. Magnet A is supplied with current from some suitable source of energy such as a battery 25 over contact 12—11—13 and a circuit controller 14 controlled in any suitable manner. When this circuit controller 14 is open the parts assume the positions shown in the drawing in which the poles of magnet A are approximately midway between the legs 6 and 7 of yoke C. If, now, circuit 70 controller 14 is closed, magnet A creates a magnetic field which tends to draw both legs 6 and 7 toward the poles 2. It is practically impossible, however, to center the magnet so accurately that the forces acting on both 75 legs are exactly equal but one leg will always be drawn more strongly than the other. Assuming that leg 6 is drawn toward the magnet more strongly than leg 7, the lug 6^a on this leg will engage arm B and 80 swing the arm to the right. As the leg 6 approaches the magnet the pull exerted on this leg is increased and at the same time leg 7 is moved away from the magnet and the pull on this latter leg is decreased. Arm 85 B is therefore swung toward the right till projection 5 moves plate 8 to the left to break the circuit for magnet A at contact 11—13. Under the influence of gravity, the arm B then swings back to its central position thus again closing the circuit for magnet A. Due, however, to the inertia of the moving parts, arm B swings past the central position and, leg 7 then being closer to the 90 magnet poles than leg 6, the arm B is drawn to the left by the magnet until the circuit for the magnet is again broken, this time at contact 12—11. It will be clear therefore that the arm B will continue to oscillate to and fro as long as magnet A is energized.

110

115

In case the amplitude of vibration of arm B builds up to such value that the inertia of the arm swings one of the legs, as leg 6, against the poles of the magnet the arm 5 can continue to move in the same direction and simply move away from the lug 6^a, engaging this lug on its return swing to move the leg 6 away from the poles again. If circuit controller 14 is opened, the signal 10 turns, under the influence of gravity, to the position shown in the drawing.

In the modification shown in Fig. 2 the arm B is pivoted as before on shaft 4 and is provided at its upper end with a yoke C¹ 15 having two upwardly projecting integral legs 6 and 7. The magnet A¹ is located above these legs with downwardly projecting poles approximately midway between legs 6 and 7 when the arm is at rest as shown 20 in the drawing.

The circuit controller J¹ comprises a shaft 15 which is operatively connected with the arm B so that when the arm oscillates the shaft also oscillates back and forth through 25 a small angle. Rigidly fastened to shaft 15 is a dog 16 comprising as best shown in Figs. 3 and 4, a flat plate 16^a outstanding from the shaft and having at its outer extremity a projection 17 extending from the face of the 30 dog and parallel with shaft 15. This dog 16 operates a disk 18 loosely mounted on shaft 15 and rotatable thereabout. The edge of this disk is provided with a notch 19 capable of receiving the projection 17 on dog 16 with considerable clearance. A contact member 11 mounted on the periphery of disk 18 co-operates with two fixed contact 35 members 12 and 13 to control the electromagnet A¹ in the same manner as explained for the control of magnet A by circuit controller J in Fig. 1. The operation of the 40 signal will be understood from the description of the operation of the signal shown in Fig. 1.

45 In the modification shown in Fig. 6, the pivoted arm B is provided with an armature C² comprising a single upstanding leg. The magnet A² is located above this armature and comprises a back strap 20 and three spaced 50 downwardly projecting poles 2, 2^a, and 2^b. A winding 20 is located on leg 2^a. The energization of this winding is controlled by a circuit controller similar to the circuit controller J¹ of Fig. 2 and omitted from Fig.

55 6 for the sake of simplicity. The parts are so proportioned that when the signal is de-energized, arm B is biased to a position in which armature C² is adjacent pole face 50^a of pole 2^a. When the signal is energized armature C² is positively drawn toward pole face 50 of pole 2 and pole face 50^b of pole 2^b alternately.

60 Signals embodying my invention are particularly adapted for, though in no way limited to, use as "three aspect signals", that

is, signals in which the signal arm is arranged to be "latched up" in an inclined position when the signal operating mechanism is de-energized.

Although I have herein shown and described only three forms of electric signals embodying my invention, it is understood that various changes and modifications may be made therein within the scope of the appended claims without departing from the 75 spirit and scope of my invention.

Having thus described my invention, what I claim is:

1. In combination, a pivoted arm biased to a central position, a magnetizable yoke 80 operatively connected with said arm and having two spaced legs, an electromagnet intermediate said legs and so disposed that when said magnet is energized one such leg is drawn toward the magnet to swing the 85 arm away from its central position, and a circuit for said magnet closed only when said arm is near such central position.

2. In combination, a pivoted arm biased to a central position, a yoke of magnetizable 90 material attached to said arm and having two upwardly projecting legs, an electromagnet having a pole located above said yoke intermediate said legs for swinging said arm alternately in opposite directions away 95 from said central position, and a circuit for said magnet responsive to the position of said arm.

3. In combination, a pivoted arm biased to a central position, a yoke of magnetizable 100 material attached to said arm and having two upwardly projecting legs, an electromagnet having a pole located above said yoke intermediate said legs for swinging said arm alternately in opposite directions 105 away from said central position, a shaft fixed to said arm and rotatable thereby, a dog rigidly fastened to said shaft and having an outstanding finger, a disk freely rotatable on said shaft and provided with a recess for 110 receiving said finger with considerable clearance, and a circuit controller operated by said disk for controlling said electromagnet.

4. In combination, a pivoted arm biased to a central position, a single magnet for 115 positively swinging said arm away from said central position alternately in opposite directions, and means for energizing said magnet only when said arm is near its central position.

5. In combination, a pivoted arm biased to a central position, a single magnet for positively swinging said arm alternately to extreme positions on opposite sides of said central position, and means for at times supplying energy to said magnet but for interrupting such supply when said arm approaches either such extreme position.

6. In combination, a pivoted arm biased to a central position, a normally closed cir- 130

cuit controller operated by said arm and arranged to be opened when said arm is moved away from such position, a single magnet for positively swinging said arm away from such central position alternately in opposite directions, and means including said circuit controller for supplying energy to said magnet.

7. In combination, a pivoted arm, a magnet, a yoke having two legs operatively connected with said arm and biased to a central position in which said magnet is between

said legs but is slightly closer to one such leg than to the other so that one said leg approaches the magnet when the magnet is energized, and a normally closed circuit controller for controlling said magnet and arranged to be opened when said arm is moved away from said central position whereby said legs are alternately swung toward said magnet to oscillate said arm.

In testimony whereof I affix my signature.

CHARLES W. DUNHAM.
